AUGUST F. KRAEMER, OF PROVIDENCE, RHODE ISLAND, ASSIGNOR TO LOUIS STERN COMPANY, OF PROVIDENCE, RHODE ISLAND, A CORPORATION OF RHODE ISLAND

EXTENSION DEVICE FOR BRACELETS

Application filed July 12, 1929. Serial No. 377,739.

This invention relates to improvements in an extension device for bracelets, more particularly for watch bracelets; and the object of this invention is to provide a plurality of sections hinged together to be unfolded to an end-to-end extended position to temporarily lengthen the bracelet to be pressed over the hand of the wearer and to fold these sections to nest one within the other; also to provide means at both ends of these folded sections for releasably securing them together.

A further object of the invention is to provide a pivot pin receiving loop on the adjacent end of each of the end members, which loops are arranged to engage one with the other to lock these ends together and to also provide cooperating detent members at the opposite ends of said members to also releasably lock these members of the device together.

With these and other objects in view, the invention consists of certain novel features of construction, as will be more fully described, and particularly pointed out in the appended claims.

In the accompanying drawings:

Fig. 1 is a top view showing my improved extension device in folded position and attached at each end of links of the bracelet.

Fig. 2 is a view of the under side of the extension device and attached to links of the bracelet.

Fig. 3 is a view of the under side of the extension device, showing the members of the device as swung to extended position.

Fig. 4 is a view of the fold of the device, showing the members in extended position.

Fig. 5 shows the members of the extension device in folded position and illustrating the loop of one of the end member as engaging that of the other end member to lock this end of these two members together.

Fig. 6 is an enlarged view of the loop ends as illustrated in Fig. 5, showing the center of the inner loop as snapping inwardly past the center of the outer loop.

Fig. 7 shows these foldable members as being in released position and partly folded.

Fig. 8 shows the three extension members as separated one from the other.

It is found in practice of advantage to lock both ends of the folded parts of an extension device so that an endwise pull on the bracelet will not serve to open up this extension device, and to accomplish this locking effect on both ends of the device, I have folded the end portion of the top wall of one of these members into a pivot pin receiving loop, and have folded the bottom wall of the adjacent end of the other member also into a pivot pin receiving loop and have arranged these loops so that one is smaller than the other and will snap by and lock or releasably retain these ends of the device in nested position. Also, I have provided a cooperating snapping detent for the opposite end of these members whereby when nested, both ends of these folding members are retained in folded position. And the following is a detailed description of the present embodiment of my invention and showing one means by which these advantageous results may be accomplished:

With reference to the drawings, 10 designates the main channel section of the extension member, which is provided with two side walls 11, and a top wall 12. One end of this top wall as best illustrated in Fig. 6, is extended and folded into a loop, as at 13, having an eye 14; through which the pivot pin 15 extends. This end wall is notched inwardly at 16, to receive a top plate of the next adjacent link of the bracelet. I have also provided a second channel section 17, which is substantially the length of the main channel section and of a width to nest within that section. This second channel section is provided with a bottom wall 18, which is folded at its end into loop shape as at 19, for the reception of its pivot pin 20, by which it is pivotally connected through the intermediate links 21, to the main channel section 10. This loop 19 on the channel section 17, is preferably of a diameter less than that of the loop 13 on the main channel section and is so arranged as to snap inwardly past the center of the loop 13 so that this end section

shall be retained when folded into nested position.

Cooperating with this pair of detent loops for one end of the extending device, I have 5 provided a detent device for the opposite end of these folding members, one form of which is herein shown as being a U-shaped member 22, which is secured to the under side of the top wall 12 of the main channel section and 10 I have also provided a stud member 23, which is secured to the inner face of the bottom wall 18, of the second channel section. This stud member is provided with a head portion 24, which snaps over the edge of the U-shaped member 22, to perform two functions: First, it releasably retains this end of the folded or nested members together; and secondly, it presses the loop-shaped member 20 against the loop-shaped member 15, thereby cooperating 15 therewith to provide a securing fastening at each end of this extension member to prevent inadvertent unfolding of these extension members when closed and locked together.

20 My improved device is very simple and practical in construction and is effective in its operation, and by its use this extension device is securely locked when in folded position.

25 The foregoing description is directed solely towards the construction illustrated, but I desire it to be understood that I reserve the privilege of resorting to all the mechanical changes to which the device is susceptible, 30 the invention being defined and limited only by the terms of the appended claims.

I claim:

1. In a bracelet, an extension device comprising a plurality of hingedly connected 40 members, the upper member having a lock loop depending from the free end thereof, the lower member having a lock loop extending upwardly from the end thereof which is adjacent the said free end when in folded position, the loop of said upper member being of larger diameter than the loop of said lower member to permit the smaller loop to snap past the center of the larger loop.
2. In a bracelet, an extension device comprising a plurality of hingedly connected members, the upper member having a lock loop depending from the free end thereof, the lower member having a lock loop extending upwardly from the end thereof which is adjacent the said free end when in folded position, said upper member loop being larger than the lower member loop and having its center positioned below the lower member loop at a distance from the upper member greater than the radius of said lower member loop to permit the lower member loop to snap past the center of the upper member loop.
3. In a bracelet, an extension device comprising a plurality of hingedly connected

members, the upper member having a lock loop depending from the free end thereof, the lower member having a lock loop extending upwardly from the end thereof which is adjacent the said free end when in folded position, the loop of said upper member being of larger diameter than the loop of said lower member to permit the smaller loop to snap past the center of the larger loop, and means for detachably securing the other ends of said members in adjacency.

4. In a bracelet, an extension device comprising a plurality of hingedly connected members, the upper member having a lock loop depending from the free end thereof, the lower member having a lock loop extending upwardly from the end thereof which is adjacent the said free end when in folded position, said upper member loop being larger than the lower member loop and having its center positioned below the lower member loop at a distance from the upper member greater than the radius of said lower member loop to permit the lower member loop to snap past the center of the upper member loop, and means for detachably securing the other ends of said members in adjacency.

In testimony whereof I affix my signature.

AUGUST F. KRAEMER.
